(57) CLAIM

The ornamental design for a worksurface as shown and described.

DESCRIPTION

FIG. 1 is a top view of a worksurface;
FIG. 2 is a bottom view of the worksurface shown in FIG. 1;

FIG. 3 is a side view of the worksurface shown in FIG. 1;
FIG. 4 is an opposite side view of the worksurface shown in FIG. 1;

FIG. 5 is a rear view of the worksurface shown in FIG. 1;
FIG. 6 is a front view of the worksurface shown in FIG. 1;
FIG. 7 is a top perspective view of the worksurface shown in FIG. 1; and,
FIG. 8 is a bottom perspective view of the worksurface shown in FIG. 1.

The broken lines showing openings in FIGS. 2 and 8 show features that form no part of the claimed design.
